UNITED STATES PATENT OFFICE.

FRANK J. BECKER, OF HAMILTON, OHIO, ASSIGNOR TO THADDEUS A. NEELY,
OF MUNCIE, INDIANA.

CORN-POPPER.

SPECIFICATION forming part of Letters Patent No. 643,103, dated February 13, 1900.

Application filed December 12, 1898. Serial No. 699,064. (No model.)

To all whom it may concern:

Be it known that I, FRANK J. BECKER, a citizen of the United States, residing at Hamilton, in the county of Butler and State of Ohio, have invented certain new and useful 5 Improvements in Corn-Poppers, of which the following is a specification.

My invention relates to corn-poppers; and the object of my improvements are to provide 10 such form of construction and aggregation of parts as will facilitate its operation and increase its efficiency. These objects are obtained in the following-described manner, as illustrated in the accompanying drawings, in 15 which—

Figure 1 is a plan; Fig. 2, an end elevation; Fig. 3, a perspective view showing a modified form of construction; Figs. 4 and 5, details of construction of the metal frames.

20 In the drawings, 1 represents the basket, and 2 the basket-lid, of similar form and preferably constructed of wire-cloth. Each is provided with a metal frame 3, and they are hinged together at 4. Said frames are each 25 formed of a single strip of tin or other sheet metal in the manner shown in Fig. 4. The corners are first formed by bending the tin over itself on a diagonal line to form a right angle, as at 15. The outside half or fold 16 30 of the strip between the adjacent corners is then turned over the inner half or fold 17, leaving slot 18 between them. The dotted lines 19 show the shape of the extremities of the tin before bending, and 20 shows the triangular lips that interlock to secure the ends of the tin together and complete one corner of the frame. The edges of the basket and of the lid are now inserted in slot 18 of respective frames and secured by crushing the folds 35 or sides of the frame closely together thereon. To better secure the edges of the basket and of the lid in the respective frames, a longitudinal corrugation or V-shaped bend 21 is pressed in each side and end of the frames, 40 as shown in Fig. 5. When closed, the basket and lid together form a cylinder with closed ends and preferably octagonal in form in cross-section. Latch 5 fastens the lid securely 45 when closed. Flat metal bar 6 is secured to

the basket-frame 3 and occupies the line of 50 its axis. Arms 7 are formed by the extension of said bar without the ends of the basket and are twisted like an auger in the form of a right and left hand screw or helix, respectively, that terminate in stops 8. 55

The popper-handle 9 is formed double and of spring-wire and coiled at its end 11 to increase its flexibility. The sides of the handle terminate in flat loops 12 to movably engage with the respective arms 7. The tendency of the sides of the handle is strongly apart and against stops 8. When the sides of the handle are pressed toward each other by the operator, the sliding engagement of the loops with the arms imparts rotary motion in one direction to the basket. When the sides of the handle are released, they separate with sufficient force to rotate the basket in the opposite direction. By alternately pressing together and releasing the sides of 70 the handle the basket is caused to rotate in opposite directions successively and to thoroughly agitate the contents and facilitate its action in obtaining the best possible results. 75

A modified form of construction is shown in Fig. 3 in that the ends of the basket and lid are formed of tin or other imperforated metal. The cylinder is round instead of octagonal in cross-section, and the arms are fastened to the respective ends of the basket 80 without being extended therethrough on its axial line. 85

Having fully described my improvement, what I claim as my invention, and desire to secure by Letters Patent, is—

1. In a corn-popper the combination with a rotary receptacle, of oppositely-twisted flat arms projecting beyond the opposite ends of the receptacle and axially with respect thereto, and a handle comprising a spring-coil and 90 terminating in flat loops engaging the twisted arms beyond the ends of the receptacle, whereby the complete rotation of the receptacle may be effected by the relative compression or expansion of the arms. 95

2. A corn-popper receptacle comprising a sheet-metal frame formed by bending a single strip of sheet metal into flat rectangular

form by overlapping the strip on an oblique line at the corners of the frame, doubling the four sides of the frame longitudinally, forming correlative longitudinal corrugations in
5 each of the frame sides and finally bending the terminals of the frame obliquely to form interlocking lips designed to connect the ends

of the strip and a wire receptacle having its edges clamped between the doubled edges of the frame, substantially as specified.

FRANK J. BECKER.
